[57] CLAIM

The ornamental design for a golf clubhead, as shown and described.

DESCRIPTION

FIG. 1 is a front elevational view of the golf clubhead;
FIG. 2 is a top plan view of the golf clubhead of FIG. 1;
FIG. 3 is a bottom plan view of the golf clubhead of FIG. 1;
FIG. 4 is a left side elevational view of the golf clubhead of FIG. 1;
FIG. 5 is a right side elevational view of the golf clubhead of FIG. 1;
FIG. 6 is a rear elevational view of the golf clubhead of FIG. 1;
FIG. 7 is a sectional view taken along the line 7—7 of FIG. 1;
FIG. 8 is a sectional view taken along the line 8—8 of FIG. 1;
FIG. 9 is a sectional view taken along the line 9—9 of FIG. 1;
FIG. 10 is a front elevational view of a second embodiment of the golf clubhead as disclosed in FIG. 1;
FIG. 11 is a top plan view of the golf clubhead of FIG. 10;
FIG. 12 is a bottom plan view of the golf clubhead of FIG. 10;
FIG. 13 is a left side elevational view of the golf clubhead of FIG. 10;
FIG. 14 is a right side elevational view of the golf clubhead of FIG. 10;
FIG. 15 is a rear elevational view of the golf clubhead of FIG. 10;
FIG. 16 is a sectional view taken on line 16—16 of FIG. 10;
FIG. 17 is a sectional view taken on line 17—17 of FIG. 10;
FIG. 18 is a sectional view taken on line 18—18 of FIG. 10;
FIG. 19 is a front elevational view of a third embodiment of the golf clubhead as disclosed in FIG. 1;
FIG. 20 is a top plan view of the golf clubhead of FIG. 19;
FIG. 21 is a bottom plan view of the golf clubhead of FIG. 19;

FIG. 22 is a left side elevational view of the golf clubhead of FIG. 19;
FIG. 23 is a right side elevational view of the golf clubhead of FIG. 19;
FIG. 24 is a rear elevational view of the golf clubhead of FIG. 19;
FIG. 25 is a sectional view taken on line 25—25 of FIG. 19;
FIG. 26 is a sectional view taken on line 26—26 of FIG. 19;
FIG. 27 is a sectional view taken on line 27—27 of FIG. 19;
FIG. 28 is a front elevational view of a forth embodiment of the golf clubhead as disclosed in FIG. 1;
FIG. 29 is a top plan view of the golf clubhead of FIG. 28;
FIG. 30 is a bottom plan view of the golf clubhead of FIG. 28;

FIG. 31 is a left side elevational view of the golf clubhead of FIG. 28;
FIG. 32 is a right side elevational view of the golf clubhead of FIG. 28;
FIG. 33 is a rear elevational view of the golf clubhead of FIG. 28;
FIG. 34 is a sectional view taken on line 34—34 of FIG. 28;
FIG. 35 is a sectional view taken on line 35—35 of FIG. 28;
and,
FIG. 36 is a sectional view taken on line 36—36 of FIG. 28.
